UNITED STATES PATENT OFFICE.

CHARLES NEWELL RAND, OF GENEVA, ASSIGNOR OF ONE-HALF TO EMERY
GALEN WETHERBEE, OF PAINESVILLE, OHIO.

ORGAN-REED-BENDING MACHINE.

SPECIFICATION forming part of Letters Patent No. 550,381, dated November 26, 1895.

Application filed December 21, 1894. Serial No. 532,610. (No model.)

To all whom it may concern:

Be it known that I, CHARLES NEWELL RAND, a citizen of the United States, and a resident of Geneva, in the county of Ashtabula and State of Ohio, have invented a new and useful Machine for Bending Organ-Reeds, of which the following is a specification.

This invention relates to bending organ-reeds, and has for its object to greatly facilitate, expedite, and perfect such work; and the invention consists in the peculiar constructions and combinations of mechanisms substantially as hereinafter described, and 15 pointed out in the claims.

In the accompanying drawings, Sheet 1, Figure 1, is a top or plan view of my new reed-bending machine. Sheet 2, Fig. 2, is a side elevation of the same. Sheet 3, Fig. 3, 20 is a front end elevation. Sheet 4, Fig. 4, is an enlarged detail view of hammer and anvil portion of the machine and accompanying mechanism in perspective, a portion of the table broken away to partly uncover hidden 25 parts. Fig. 5 is a sectional view of the hammer and anvil and their supports, showing a pair of bending-dies in their relative positions in the hammer and anvil, also showing a reed in section over the anvil-die and other 30 reeds on the table to follow said sectional reed in the operations of the machine.

A is the table or bed of the machine supported on suitable legs.

B is a table or tray consisting of a sheet of 35 spring steel and is supported at its front end at the front side of the table or bed A by two legs $b\ b$ and at a distance a little less than half its length by two other legs $b^2\ b^2$. The balance of the table B is left unsupported by 40 legs or otherwise to allow it to be sprung, for a purpose hereinafter shown.

C C are guide-pieces pivoted at the heel to the table B at $c\ c$, leaving their points free to be moved for expanding or contracting the 45 space between them. C² is a curved spring standing over said guides near the pivoted ends and having one end secured to the table at c^2 , close to the guide-piece, the other end being left free to bear against the side of the 50 other guide-piece, the purpose of which is to provide for friction-bearing of the guides against the reeds as they are passed between them in the operations of the machine.

C³ and C⁴ are other permanent guides fixed to the table B, in the forward end of which 55 is placed a sliding feed-bar C⁵, operated by means of a lever D, fulcrumed underneath the table A and actuated by means herein-after described.

E is a bed-plate securely attached to the 60 table A in advance of the spring-table B and supporting the heavier working parts of the machine.

F F are two posts attached to and supported on the bed-plate E at the central part of the 65 table A and adjoining the spring-table or tray B. G is an anvil fixed between the feet of said posts F F and directly under the springing end of said table B. The tops of 70 said posts F F are joined by a cap-plate F². H is a hammer fixed on the end of a lever I to play between said posts and over the said anvil and spring-table. The lever I is fulcrumed in a post J near the rear end of the bed-plate E.

h h are removable dies set in slots in the anvil and hammer, having properly curved 75 faces for making a bend in the point of the reed. A set of such dies is provided for all sizes of reeds.

K K are posts or pillow-blocks standing on the back corners of the bed-plate E, in which is supported a shaft L, carrying a disk or wheel M, having a pin m, which as the disk revolves strikes the end of the lever I, depressing that end and raising the hammer for 80 making a stroke.

N is a curved spring attached to the cap-plate F² with its lower end bearing on the lever I. O is also a curved spring, secured to 90 the bed-plate E near the post J, its upper end bearing on the under side of said lever I. The spring O serves to hold the hammer up while the disk M is rotating and carrying the pin m around after it has operated on the lever, so that the bent reed may be pushed 95 from under the hammer and another reed pushed forward to take its place. The spring N serves to prevent the hammer being thrown upward with force and striking against the 100 cross-cap piece F².

P is a curved spring attached to the top of the hammer and extending downward over the spring-table, and is designed for depressing 105 said table to bring the point of the reed down onto the anvil just as the stroke is

made. As the hammer rises again the table springs up again and frees the reed, so that it may be pushed forward and delivered onto a receiving table or tray X.

5 On the left-hand end of the shaft L is attached a crank-disk Q, to which is attached one end of a connecting-rod D², the other end of which is adjustably attached to the lever D, extending up through a slot in the table A.

10 R R are hangers secured to the under side of the table A, supporting a short shaft R², on which is attached the levers D and D³. Lever D³ extends up through a slot in the table and through a slot in push-bar C⁵, by means 15 of which said push-bar pushes the reeds along in succession under the hammer.

D⁸ is a post attached to the under side of the table, to the lower end of which is pivoted at its angle an angle-lever D⁴, one end of 20 which is adjustably connected by a rod D⁵ with the slotted lever D³. The other arm of lever D⁵ carries the vertical rod D⁷, that is connected with the push plate and bar X². This push bar and plate work in conjunction 25 with the push-bar C⁵, so that as a reed is being pushed out from the guides C C onto the table X the bar and plate X² are drawn back to make room for said reed to pass onto the table X.

30 On right-hand end of shaft L is placed a loose driving-pulley S, provided with a clutch T.

U² is a post supported on an arm U on the bed-plate E.

35 V is a hand-lever pivoted to the top of post U², one end engaging under a disk y on driving-pulley S, by means of which said driving-pulley and clutch T are thrown into and out of engagement with the shaft L for starting 40 or stopping the machine.

W is a reed-holding galley or tray, supported in an inclined position by means of a vertical rod W², held in a screw-clamp W³, attached to the left-hand side of the table A.

45 The lower end of said galley or tray is set upon the table B, so as to deliver the reeds thereon by gravity, the reeds placed side by side sliding down as the lowest one is pushed away.

50 X is a receiving-table supported transversely to and close to the end of the table B, upon which the reeds are delivered and upon which reeds are conveyed side by side to a receiving galley or tray W⁴, supported 55 at the right-hand side of the machine.

The operations of the machine are as follows: A galley or tray W, containing reeds to be operated upon, placed side by side in the order as shown in Figs. 1 and 4, is set 60 upon the machine in an inclined position, with the lower end adjusted so as to have the reeds slide down onto the table B by their own gravity, the lowest reed passing in front of the push-bar C⁵. An empty galley or tray 65 is also attached to the machine, as seen at W⁴, connected to and in line with the table

X. The machine is now ready for operation, and the driving-pulley being put into engagement with the shaft L, the work proceeds as follows: The push-bar C⁵ is given a reciprocating movement, which pushes the lowest reed in the column from the feed-galley forward toward the hammer, at the same time the push-plate X² is drawn back through the medium of the angle-lever D⁵ and vertical arm D⁷, at the same time also the hammer has been lifted and falls. These working parts of the machine are so adjusted that a reed is carried over the anvil, and while the push-bar C⁵ is receding the hammer falls. 70 The downward movement of the hammer depresses the spring-table B through the medium of the spring-arm P. This brings the point of the reed-tongue down onto the anvil-die, as seen at Fig. 5, and the stroke of the 75 hammer bends the point. The hammer is moved upward immediately after the stroke by the spring O. This relieves the pressure of the spring-arm P on the table B and frees the reed from the anvil, and now the forward movement of the push-bar C⁵ is repeated and the reed just operated upon is pushed forward above the anvil and onto the receiving-table X, and the next reed follows and takes 80 its place over the anvil. At the same time the 85 push-plate X² pushes the finished reeds along on the table X toward the receiving-galley.

It will thus be seen that the machine is very rapid and perfect in its work, giving an exact uniformity in the bend of the reeds.

Having described my invention, I claim—

1. In an organ reed bending machine, the combination of the table A, the springing table B mounted thereon, the pivoted guides C C, the spring C² actuating said guides, the permanent guides C³ and C⁴ and the sliding feed bar C⁵, playing in said permanent guides adapted to operate, substantially as described. 105

2. In an organ reed bending machine, the combination of the table "A," the spring table "B" mounted thereon, the pivoted guides "C C," the spring "C²" actuating said guides, the permanent guides "C³ and C⁴," the inclined feed galley "W," and the sliding feed bar "C⁵" playing in said permanent 115 guides, adapted to convey reeds from the foot of said galley substantially as described.

3. In an organ reed bending machine, the combination of the table "A," the spring table "B" mounted thereon, the pivoted guides "C C," the spring "C²" actuating said guides, the permanent guides "C³" and "C⁴," the inclined feed galley "W," the sliding feed bar "C⁵" playing in said permanent 120 guides, the anvil "G" and the hammer "H," 125 and means for operating the hammer in conjunction with the feed mechanism substantially as described.

CHARLES NEWELL RAND.
